UNITED STATES PATENT OFFICE.

JAMES B. ROBERTS AND CHRISTIAN SCHAFER, OF THREE RIVERS,
MICHIGAN; SAID SCHAFER ASSIGNOR TO SAID ROBERTS.

GRAIN-SEPARATOR.

SPECIFICATION forming part of Letters Patent No. 239,060, dated March 22, 1881.

Application filed February 24, 1880.

To all whom it may concern:

Be it known that we, JAMES B. ROBERTS and CHRISTIAN SCHAFER, both of Three Rivers, in the county of St. Joseph and State of Michigan, have invented a certain new and useful Improvement in Grain-Separators, of which the following is a full, clear, and exact description, reference being had to the accompanying drawings, forming part of this specification.

Our improvement consists, first, in a separating-shoe and fan, which we combine with a still-air chamber, an adjustable shed delivering upon the straw-carrier, and a conveyer.

Our improvement consists, further, in combining a fan, a reciprocating shoe having boards and a screen, an adjustable shed delivering on the straw-carrier and a receptacle beyond, with conveyers, all arranged and operating within the housing of the machine, as hereinafter described.

Our improvement consists, further, in a separating-shoe located within the main case above the vibrating pans and discharging the material blown from the tail of the shoe into the main case above the said vibrating pans, substantially as hereinafter described.

In the drawings, Figure 1 is a side elevation of the machine as viewed from one side, and Fig. 2 is an elevation of the other side. Fig. 3 is a longitudinal section. Fig. 4 is a detail top view of the tailing-trough and connections.

A A are the wheels, B B the frame, C C the sides, and D the top, of the body.

E is the mouth, into which the sheaves are fed. (A part of this only is shown.)

F is the toothed cylinder, and F' its shaft, carrying a belt-pulley, by which it is turned.

G is the concave.

H is the rotary beater. H' is the shaft of the same, carrying a belt-pulley, by which it is turned. The beater is interposed between the cylinder and the box or case of the upper fan or blower to prevent the impingement of the straw against the fan-box and consequent stoppage and clogging of the same.

I is the first vibrating fan supported by eye-lugs J, which work on guide-rods K, attached

to the sides of the machine. The vibrating fans are reciprocated in a direction endwise to the machine by a compound crank-shaft, L, which is the main shaft of the machine. Connection between the crank-shaft L and the vibrating pans is made by connecting-rods M and M' and the lugs N secured to the bottom of the pans. The bottom of pan I is without orifices. Its sides and front end are high enough to prevent the escape of its contents, except at the rear end, where it laps over the second vibrating pan, O. The front portion, O', of pan O is imperforate, like that I; but the rear portion has orifices, through which the grain drops upon the inclined board or deflector P, over which it slides to the receptacle or hopper Q, while a part of the grain drops from the riddle O² direct into the receptacle Q, from which it is carried by a rotary conveyer. The straw and chaff pass out through the tail of the machine.

R is a fan, operated and operating in the usual way.

The inclined board P acts as a deflector of the blast, to prevent its impinging directly upon the riddle O², and thus checking the downward passage of the grain through it.

S is an inclined board, which receives the grain (and seeds, if the latter are present) carried over the tail end of the riddle O². This inclined board acts as a deflector, to direct the blast upward through the oscillating rake or comb T². There are three of these rakes, T T' T², all having bearing in the pan O, and caused to oscillate by the movement of the pan by means of arms t', extending upward from the rocking heads or shafts t, the said arms having slots at the upper end to receive a stud, t², fixed in the side of the machine. This device is not new in this application, and requires no further description.

U is a spiral conveyer, of usual form, in the bottom of the box or receptacle Q, and turned by a belt-pulley, V. This conveyer carries the contents of box Q sidewise into the bottom of the elevator-trunk W, whence it is carried by the buckets x of the elevator X to the chute or spout Y, through which it descends upon the vibrating shoe Z. The shoe is suspended on

hangers *a*, having bearing, by side pins at their upper ends, in the sides *C* of the body. The shoe receives its motion (which is endwise to the machine) from an oscillating lever, *b*, that is hinged to one of the sides *C*, and is caused to oscillate by a lever, *c*, that passes through it and through a fulcrum-eye, *d*, and whose lower end is turned inward, and is connected to the pan *O*, extending through an orifice in the side *C*. The connection between the lever *b* and the shoe is made by a link, *e*, pivoted to the lever, and connected to the shoe by a pin or stud, *f*, descending from the shoe and passing through the link. The shoe *Z* has inclined boards *z* and *z'* and a screen, *z''*. The grain passes over the screen and drops off the front edge into the conveyer-trough *g*, and is carried by an ordinary spiral conveyer, *h*, into the sacker and measurer *i*. The conveyer is rotated by a belt-pulley, *h'*, on its shaft.

The sacker *i* is not a novel feature in this invention, except in combination with the reversible spiral conveyer *h* and such construction of machine as allows the sacker to be attached to either side of the machine so that the cleaned grain may be taken from either side, as may be most convenient. The attachment is made by an orifice in the sacker, which fits on the mouth of the conveyer-trough, and on which it is held by a button, *i'*, and by pins at the inner side of the sacker, which rest in staples *i'*. The conveyer *h* is made reversible by a straight or twisted belt on the pulley *h'*. The bag-holder at the bottom of the sacker has a curved toothed bar, *j*, hinged at the ends to the sacker, and operated by a handle, *j'*, held up by a ratchet-rack, *j''*.

The operation of the shoe *Z* is as follows: The grain, divested of the straw and most or all of the chaff, is delivered by the elevator *X* and chute or spout *Y* onto the inclined board or plate *z*, and falls from its lower edge upon the screen *z''*. The grain falls from the front end of the screen into the trough *g*. The tailings are carried back by the blast from the fan *k* and drop into the tailings-trough *l*. This trough works transversely in the shoe, and is inclined downward to the discharging end *l*, where the tailings fall into the hopper *m'* at the lower end of the elevator *m*, and are discharged at the upper end of the elevator into a trough, *n*, by which the tailings are conducted to the mouth of the machine. There is nothing new in this elevator, except in its connection with the transversely-reciprocating tailings-trough *l* and elevated shoe *Z*. The grass-seed and other small seeds fall through the screen *z''*, and are subjected to the force of the blast (from fan *k*) and carried over the adjustable board *o*, and over that *p* into the hopper or box *q*. The box *q* has the form of a trough with inclined sides *q'* and *q''* extending from side to side of the body. In the bottom of the box or hopper *q* is a spiral conveyer, *s*, carrying the seeds out through a

spout, *s'*, to which a bag may be hung, or beneath which a vessel may be placed, to receive the seeds. The conveyer *s* is rotated by a belt-pulley, *s''*.

In Fig. 4 is shown a top view of the tailings-trough with the operating-levers connected to it to cause its endwise reciprocation in direction at a right angle with the direction of movement of the shoe. In this figure there are boards *z* of the shoe descending into the trough, inside its sides, so as to guide all the tailings into the trough. The trough is supported in hanger-stirrups *z'*, attached to the shoe. The position of the sides *C* of the body and of the sides of the shoe is shown by dotted lines in Fig. 4. The tailings-trough has, of course, vibratory motion with the shoe. The transverse motion of the trough is imparted to it by the lever *b* through the medium of the connecting-rod *b'* and the bell-crank or angle-lever *b''*, the connecting-rod engaging with the lever *b* by its down-turned end passing through said lever, and the other end being similarly connected to the bell-crank lever *b''*. The inner arm of the bell-crank lever extends along outside the side *C* of the body, and has a downward stud, *b''*, passing through a slot in a lug, *l'*, extending from the tailings-trough *l*.

The operation has been described in detail.

Some of the advantages of the invention may be briefly stated as follows: By only partly separating the grain from the other matters in the lower part of the machine we are enabled to use shorter pans and a smaller fan with a single perforate riddle, *o*. This modification in construction shortens the body, and by the decrease in height of these parts (chiefly owing to the decreased size of the fan) we are enabled to place the feed-mouth and cylinder much nearer to the ground, thus considerably decreasing the labor of passing sheaves to the feeder. The grain being carried upward and forward is delivered to the sacker from a greater elevation, and has a second course backward through the body of the machine, where the different matters are separated much more perfectly can be done with one operation. Thus the small seeds are screened out of the grain and blown with a strong blast over the two inclined boards *o* and *p*, and subside in the still-air chamber to the rear of board *p*. The tailings are carried away by trough *l*, and the larger and lighter impurities are blown over the board *o*, and fall down upon the matter, passing over the pans, being carried forward by the inclined board *p*, so that any grain may have sufficient opportunity to pass down through the straw and fall into the box *q*.

We claim as our invention—

1. The combination of separating-shoe *Z* and fan *k* with still-air chamber *q*, adjustable shed *p*, delivering upon the straw-carrier *O*, and conveyer *s*, as and for the purpose set forth.

2. The combination of fan *k*, reciprocating shoe *Z*, having the parts *z*, *z'*, *z''*, *z'''*, and *o*,

adjustable shed *p*, delivering on the straw carrier and receptacle *q* beyond, with the conveyors *h*, *z*⁴, and *s*, all arranged and operating within the housing of the machine, substantially as set forth.

5. The separating-shoe *Z*, located within the main case above the vibrating pans and discharging the material blown from the tail of

the shoe into the main case above said vibrating-pans, substantially as and for the purposes to set forth.

JAMES B. ROBERTS.
CHRISTIAN SCHAFER.
